UNITED STATES PATENT OFFICE

JOHN KENNETH KING, OF GLENWOOD SPRINGS, COLORADO, ASSIGNOR TO ROYAL DISPLAY, INC., A CORPORATION OF WASHINGTON

ILLUMINATED SIGN

Application filed November 24, 1928. Serial No. 321,684.

This invention has relation to display apparatus, such as signs, signals, direction indicators, advertisements, and the like in which the matter to be displayed is in the form of a stenciled plate or other similar device through which rays of light are transmitted from a light giving medium located behind the same.

The object of the invention is to provide certain improvements in display apparatus of the above recited character employing Geisler tubes, or other light giving tubes, containing gases which are rendered luminous by the action of an electric current of high tension. These improvements consist in the construction of an apparatus wherein the light from the gaseous element will be projected through the sign or foreground by means of suitable reflectors or mirrors, while the Geisler or like tubes will be concealed, or so located that the rays therefrom will not be directly projected therefrom.

In the accompanying drawing illustrating preferred embodiments of the invention under consideration,

Figure 1 is a front view of a display device comprising a housing or casing adapted to contain the lighting tubes and appurtenant devices and the mirrors or reflectors, and having a stenciled face plate for the passage of the light rays;

Figure 2 is a plan view of the same;

Figure 3 is a view similar to Figure 1, with the stencil plate omitted to disclose the interior mirror or reflector equipment;

Figure 4 is a similar view, with the mirrors or reflectors omitted to disclose parts of the electrical equipment;

Figure 5 is a horizontal sectional view of the apparatus;

Figure 6 is a vertical transverse sectional view of one form of the apparatus in which concave reflectors are employed;

Figure 7 is a diagrammatic view, in perspective, of the Geisler tube arrangement; and

Figure 8 is a vertical transverse sectional view of the apparatus equipped with plane mirrors or reflecting surfaces instead of concave reflectors.

Figure 9 is a diagrammatic view showing the light distribution in the form shown in Figure 8.

The numeral 1 designates a rectangular, oblong casing or housing of metal or other suitable material composed of the back wall 2, top and bottom walls, 3 and 4, respectively, end walls 3', 4' and the front panel 5, the last named being either a stenciled plate or a glass plate upon which are produced the letters, numbers or legends which are to be displayed.

The size, particular shape and other minor features of the apparatus will depend upon the special uses and locations as for highway signals, street indicators, directory boards and the like and may be varied accordingly.

The numerals 6 and 7 designate Geisler tubes or other equivalent electrically illuminated gas tubes, located horizontally at the upper and lower parts of the casing and within the same.

These tubes are mounted at their ends on the blocks 8, to which are attached circuit terminals or binding posts 9, connected to the secondary coil of a transformer 10, the primary of which is fed from a suitable generator located outside the casing.

The tubes 6 and 7 are bent to rectangular form, the transverse sections 11, being located at the ends of the casing and the main illuminating sections 12 located near the front of the casing and running lengthwise of the latter. They are preferably disposed out of sight by the framing 12' of the casing.

In the form of the apparatus shown in Figure 6, the light from the Geisler tubes is reflected forward by means of the concave reflectors 13, 13 located behind and facing the stenciled or translucent front of the casing, the illuminating tubes being positioned in the focuses of the reflectors, which project the rays forward in parallelism.

In the form of the apparatus shown in Figure 8, a series of plane mirrors 14 are arranged in zig-zag relation, in which position the direct light from the tubes will be cast on the mirror sections facing the same, and will be indirectly projected forward and through

the open or transparent parts of the front panel of the casing, it being understood that the reflecting surfaces are disposed at proper angles, to the vertical plane so as to reflect the rays forward or horizontally.

5. Different and attractive color effects may be produced in various ways, as by the use of different colored glass for the reflectors and mirrors; or by the use of strips of glass of 10 different color in the front of the casing, or by using different gases in the respective tubes, which will be of different colors when illuminated. By referring to Figure 9 it can there be seen that if the lower tube 7 be of 15 one color the light rays will be reflected from the reflector surfaces A and strike the screen in bands A' while rays of another color emanating from tube 6 will be reflected from the surfaces B and produce bands B' of that color 20 which will show through the open spaces on the screen or plate 5. Obviously, where rays from both lamps mingle, a color corresponding to a blend of the two will be produced. For instance, if the two lamps emit red and 25 blue rays respectively, a part of the screen will show purple.

The casing may be equipped with any desired number of reflecting mediums, so located that they will reflect the rays from the 30 tubes through different portions of the foreground panels or stencils.

It is to be understood that the main object of the invention is to permit of the advantageous and economical use of Geisler tubes 35 for signal or display purposes without incurring any of their objections or disadvantages. Where the light is projected directly from the tubes toward the foreground or through display planes, it is objectionable by reason of its 40 intense glare and penetration. This is overcome by the present invention by which the rays from the tubes are reflected and thus reduced in brilliancy and diffused, so as to be clearly seen without causing disagreeable 45 sensations to the eyes of the observer.

By the use of the Geisler tubes or their known equivalents the light may be efficiently produced and managed at less cost and by the use of simpler appliance than are requisite 50 for other methods of illumination.

I claim:—

1. In an illuminated sign, a pair of light emitting tubes emitting light of different colors and extending in spaced parallel relation, a light receiving surface having transparent portions arranged to form a sign and located in front of and shielded from direct rays from said tubes, a series of spaced light reflecting surfaces positioned to receive rays 55 from one of said tubes and to reflect the rays to spaced portions of the light receiving surface, and a second series of spaced light reflecting surfaces arranged alternately with the surfaces of the first series, to receive rays 60 from the remaining tube only and to reflect 65 them to the light receiving surface to cover other spaced portions thereof alternately with the spaces covered by the rays from the first tube.

2. In an illuminated sign, a pair of light emitting tubes emitting light of different colors extending in spaced parallel relation, a light receiving surface having transparent portions arranged to form a sign and located in front of and shielded from direct rays from

70 said tubes, a series of spaced light reflecting surfaces positioned to receive rays from one of said tubes and to reflect the rays to spaced portions of the light receiving surface, and a second series of spaced light reflecting surfaces arranged alternately with the surfaces of the first series, to receive rays from the remaining tube only and to reflect them to the light receiving surface to cover other spaced portions thereof alternately with the spaces covered by the rays from the first tube, one reflecting surface receiving light from one tube and a second reflecting surface receiving light from the other tube being arranged to reflect the received light at least partially on the same area of the light receiving surface to cause blending of the two colors on said area.

In testimony whereof I affix my signature.

J. KENNETH KING.
